UNITED STATES PATENT OFFICE.

SAMUEL ABRAHIMS NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

COLUMN-RULE.

1,194,868.

Specification of Letters Patent. Patented Aug. 15, 1916.

Application filed April 10, 1913. Serial No. 760,228.

To all whom it may concern:

Be it known that I, SAMUEL A. NEIDICH, a citizen of the United States, residing at Edgewater Park, in the county of Burlington and State of New Jersey, have invented a certain new and useful Improvement in Column-Rules, of which the following is a full, clear, and exact description, reference being had to the accompanying drawings.

My improvement is particularly applicable to printing machines of the type known commercially as the "Multigraph" comprising a rotary printing cylinder having a series of undercut channels in its perimeter extending parallel with its axis to receive complementary shaped flanged type which said cylinder presents in opposition to the other member of the printing couple. As ordinarily constructed, the only means with which such a machine is provided for printing lines at right angles to the lines of letter type consists of type fitting to the channels and having dash faces. Consequently, a series of such separate type must be used to print a line of greater extent than the dash carried by the face of a single type, and, unless said line type are accurately set and provided with means to hold them in alignment they print a broken line instead of the continuous line desired.

Therefore, it is the object of my invention to provide such a machine with means to present a continuous printing face to print lines at right angles to the lines of words, and, as hereinafter described, such means includes a rule strip curved to fit circumferentially upon said printing cylinder and having means fitting in said undercut channels thereof adapted to retain it in set position.

My invention comprises the various novel features of construction and arrangement hereinafter more definitely specified.

In the drawings, Figure I is a plan or development of a portion of a rotary printing drum or segmental typeholder adapted to carry my column rules and type; Fig. II is a cross section of a portion of such type-holding drum or segment; Fig. III is a side elevation of one form of the column rule; Fig. IV is an edge view thereof; Fig. V is a side elevation of the column rule adapted to print two parallel lines; Fig. VI is an edge view thereof; Fig. VII is an end view

of the type used on a printing drum or segment; Fig. VIII is a face view or plan of one form of such type for printing a single horizontal line; Fig. IX is a similar view of the type for printing parallel lines. The 60 form shown in Fig. I is made up of the rules and type shown in Figs. III to IX inclusive.

As shown in the drawings, 1 indicates the body of a segment or radial printing drum, 2 parallel rails carried thereby having overhanging edges leaving undercut channels 4 between the rails. The type, designated 5, have grooves 6 in their sides, so that they are adapted to be slid endwise into the space between the rails and are held by the overhanging flanges 3 occupying the grooves 6. My column rule consists of a strip 8 curved to seat on the periphery of the rails transversely to the type lines, and having on its concave side tongues or lugs 9 with projecting inner flanges or under hanging portions 10. These flanges correspond in position to the feet of the type, and the shank of the lugs to the shank of the type between the grooves 6. Thus, the rules are adapted 70 to be put in place by shoving them lengthwise on the drum or segment. When in place they are prevented from shifting laterally by the type abutting them on opposite sides.

Figs. V and VI show a column rule 8^a for printing two parallel lines. In this case the rule is made thicker and grooved about its peripheral edge, as at 11, or the same result may be obtained by bending the 90 piece of sheet metal to present the two peripheral edges which are spaced by an intermediate portion. In either case, this double line rule has inwardly projecting lugs 9 with spreading feet 10, the same as in 95 the case of the rule 8.

Such rules as described may very conveniently be mounted on a drum or segment and print the vertical columns of matter. These rules may be associated with letter or 100 numeral type to print words and figures occupying the columns, or they may be associated with horizontal rule type, so as to print a box form of ruling. Such is the make-up shown in Fig. I, where the rules 8 and 8^a are separated and held against displacement by type carrying horizontal rule lines. A single horizontal rule is shown at 12 on the face of the type in Figs. VII and VIII and in Fig. I. A double ruling 110

on the face of the type is shown at 13 in Fig. IX and in Fig. I. Of course, type might be used having no characters whatever (*i. e.*, quads) to hold the rules against lateral shifting, if it were desired to print nothing but vertical lines.

It will be seen that my column rule may be very cheaply constructed and may be easily put in place on a drum, and, when 10 in place, is held independently of the type and is designed to print vertical rules with or without horizontal matter, as desired.

I do not desire to limit myself to the precise details of construction and arrangement 15 above described, as it is obvious that various modifications may be made therein without departing from the essential features of my invention, as defined in the appended claims.

Having thus described my invention, what 20 I claim is:

1. A column rule consisting of an arcual strip having on its concave edge intermediate of the ends thereof, tongues integral with the strip which extend inwardly and 25 project at their ends substantially circumferentially, whereby they may hook beneath overhanging rails on a type holder.

2. A column rule consisting of a curved strip having tongues projecting inwardly 30 from the concave edge, said tongues extending circumferentially at their inner ends.

3. A column rule consisting of a curved strip having a tongue projecting from the 35 concave edge, the lower portion of the tongue extending at an angle to the shank of the tongue.

4. A column rule consisting of an arcual strip having radial tongues projecting from 40 the concave edge, said tongues extending circumferentially in the plane of the strip near their inner ends to enable them to hook under overhanging rails.

5. A column rule comprising a curved strip and a series of tongues located at 45 intervals on the concave edge of the strip, said tongues projecting both inwardly and longitudinally of the strip.

6. A column rule made of a single integral 50 piece and comprising a curved strip and a series of equidistant underhanging tongues on the concave edge of the strip.

7. In a duplicating machine, the combination, with a rotary printing drum having a 55 plurality of undercut channels in its periphery, of type having flanges fitted in said channels; and, a rule strip having a printing surface curved in concentric relation with said drum, held between said flanged type, 60 having lugs fitted in said channels and having flanges engaged by the overhanging ledges in said channels.

8. The combination, with grooved type 65 and a holder therefor having overhanging rails, of a column rule adapted to be mount-

ed on the face of such holder between type in lines, said rule comprising a strip the height of which is equivalent to the projection of the type above the rails, and means on the strip adapted to engage beneath the 70 heads of such overhanging rails.

9. The combination, with grooved type and a drum-like holder therefor having parallel longitudinal overhanging rails, of a 75 column rule adapted to be mounted on the face of such holder between type in lines and comprising an arcual strip the radial dimension of which is equivalent to the amount of projection of the type above the holder, said strip being provided with underhanging tongues adapted to engage beneath overhanging heads of such rails.

10. The combination, with overhanging rails and mean for holding them parallel with each other and equidistant from an axis 85 to constitute a drum type holder, grooved type adapted to stand in longitudinal lines between such rails and project beyond the heads thereof, and a column rule adapted to be mounted on the face of such holder extending across the rails between type carried by the rails, said rule being made of a single integral piece of metal and comprising a curved strip, the radial dimension of which is substantially equal to the height of the 90 type above the rails, said strip having portions formed to extend beneath the heads of some of said rails.

11. A column rule for use on a drum-like holder having longitudinal undercut channels, comprising an arcual strip, and holding means adapted to occupy some of such channels and extend into the undercut portion 100 thereof.

12. A printer's rule comprising a continuous strip, and a series of members on the under side of the strip adapted to extend beneath the heads of overhanging rails and lock the rule thereto.

13. The combination, with a printing device having a series of parallel rails with overhanging edges, of a printer's rule comprising a continuous strip, and a series of members extending inwardly from the strip and adapted to occupy spaces between the 110 adjacent rails and extend beneath the heads thereof.

14. A printer's rule for use on a rotary printing machine comprising an arcual strip concentric of the printing cylinder, and inwardly projecting members rigid with the strip having laterally projecting feet adapted to engage beneath the heads of rails on the printing cylinder.

15. The combination, with a rotary printing drum having rails parallel with its axis, of a printer's rule having a strip curved concentrically of the drum, and members extending inwardly from the strip into the space between rails and projecting circum- 125 130

ferentially in such space to engage beneath the rail heads.

16. In a duplicating machine, the combination of a rotary printing drum having a plurality of undercut channels in its periphery, a rule strip having a printing surface curved in concentric relation with said drum and adapted to be held between grooved type occupying the channels, and holding-means fitted in said channels and having flanges engaged by overhanging ledges of the channels.

17. A column rule consisting of a curved strip having a tongue projecting from the concave edge, a lower portion of the tongue extending at an angle to the portion of the strip which carries it. 15

In testimony whereof, I hereunto affix my signature in the presence of two witnesses.

SAMUEL ABRAHIMS NEIDICH.
